UNITED STATES PATENT OFFICE

CHARLES B. CUSHWA, OF YOUNGSTOWN, OHIO, ASSIGNOR TO THE COMMERCIAL SHEARING & STAMPING COMPANY, OF YOUNGSTOWN, OHIO, A CORPORATION OF OHIO

APPARATUS FOR MAKING DISHED HEADS

Application filed March 15, 1926. Serial No. 94,724.

This invention relates to the making of dished metal heads from sheet metal, and is particularly valuable in the manufacture of large sized metal heads, such as are used 5 for tank cars and the like.

Small metal heads have been made out of ductile materials, such as copper, by spinning a flat sheet over a form into the desired shape, but this practice has not been followed in 10 the working of ferrous material, such as sheet iron or steel, because of the entirely different properties of the metal. The general practice in making a large dished head out of sheet steel has been to first form a circular 15 blank and then roughly flange the same at a red heat. The flanged blank is then reheated and placed between dies that dish the head as desired. It has been necessary to then square up the flange in order to produce a finished head.

I provide for flanging the edge of a blank and then progressively dishing the blank from the center thereof toward the flange. The operation is preferably carried out at a 25 single station by first clamping the center portion of a substantially flat blank, then rounding the same, then flanging the blank while leaving it clamped, and while still maintaining the center clamped, progressively working the metal from the center to 30 the flange into dish form. With this process the heating and reheating operations and the squaring up or trimming of the flange are done away with.

35 In the accompanying drawings, which illustrate diagrammatically the steps in the making of a dished head according to my invention,—

40 Figure 1 is a vertical section through an apparatus for carrying out my improved method of making dished heads; and

45 Figures 2, 3, 4 and 5 are similar views to reduced scale showing successive steps in the operation.

50 In the illustrated embodiment of the invention there is shown a former 2 mounted on a rotatable support 3. A rotatable clamp member 4 is provided, and this is movable toward and away from the former 2. A sub-

stantially flat plate 5 is clamped between the former 2 and the clamp member 4.

When the flat plate 5 is thus clamped it is supported near its edges by a supporting ring 6, but it overhangs this ring in an amount depending on the width of the flange to be provided on the head. The supporting ring 6 is provided with supporting arms 7 and is arranged to be moved vertically with respect to the form 2. The ring 6 rotates with the 55 form 2.

When the sheet 5 is first clamped, it will generally be non-circular with respect to the axis of rotation of the form 2, and may even be a rectangular plate. A cutting tool 8 is first applied for rounding the plate by removing the excess metal 9. One or more flanging tools, such as 10, are then applied to the overhanging edge of the plate and there is produced a flat flanged plate such as shown 60 in Figure 2. It will be noted that the flange is of a width substantially corresponding to the amount the flat plate 5 overhung the ring 6 after being rounded.

The head is dished by working the metal 75 progressively from the center toward the flange, which is indicated by the reference character 11. The dishing is accomplished by one or more tools 12 adapted to bear against the metal and force it onto the top of 80 the form 2 while progressively moving outward toward the flange 11. As the tools 12 move outwardly the supporting ring 6 is lowered, so that at an intermediate stage 85 of the operation the tank head appears as shown in Figure 3.

When the tools 12 have reached the periphery of the form 2, the head is as shown in Figure 4, but it is preferred that the forming tools be moved still further outwardly 90 and the supporting ring 6 still further lowered, as shown in Figure 5. This effectually carries the curvature of the head all the way out to the rim, as is desired.

Generally, there will be no further operations required on tank heads manufactured according to my invention. The numerous disadvantages of the old process are eliminated by my new process and apparatus. The invention is not limited to the manufacture 95 100

of large dished heads, nor to the manufacture of dished heads from ferrous material, although certain features of the invention will find their broadest application in such field.

5 The term "dished head" is a term of definition and not of limitation, and is intended to include any article made from sheet metal having a peripheral flange and a bulged portion within the flange. I have illustrated and
10 described a preferred process and apparatus for carrying out my invention, but it will be understood that the invention is not limited to the form shown and described but may
15 be otherwise embodied and practiced within the scope of the following claims.

I claim:

1. Apparatus for making dished metal heads, including a form, means for supporting a blank thereon, means for rounding the blank, means for flanging the blank, and means for progressively working the metal from the central portion of the form toward the flange.
- 20 2. Apparatus for making dished metal heads, including a form, a ring surrounding the same, a cutting tool adapted to round the blank, flanging means cooperating with the ring, and a dishing tool cooperating with the form and adapted to progressively work on the blank from the central portion thereof toward the periphery of the blank.
- 25 3. In testimony whereof I have hereunto set my hand.

35
